DRESSER FOR CENTERLESS GRINDERS AND THE LIKE

Jerome H. Newman, 13971 Skyline Blvd.,
Oakland, Calif.

Filed Nov. 7, 1960, Ser. No. 62,920

Term of patent 3½ years

(Cl. D37—1)

FIG. 1.

FIG. 2.

FIG. 4.

FIG. 3.

The dominant portions of my design are indicated by solid lines in the drawing.

I claim:

The ornamental design for a dresser for centerless grinders and the like, substantially as shown and described.
